CLAIM

The ornamental design for a tabletop corner, as shown and described.

DESCRIPTION

FIG. 1 is a top perspective view of a first embodiment of a tabletop corner showing my new design;

FIG. 2 is an enlarged detailed view taken from the boxed area 2 shown on FIG. 1;

FIG. 3 is right-side view of the tabletop corner shown in FIG. 2;

FIG. 4 is a left-side view of the tabletop corner shown in FIG. 2;

FIG. 5 is a top view of the tabletop corner shown in FIG. 2;

FIG. 6 is a top perspective view of a second embodiment of a tabletop corner showing my new design;

FIG. 7 is a bottom perspective view of the second embodiment of a tabletop corner;

FIG. 8 is an enlarged detailed view taken from the boxed area 8 shown on FIG. 6;

FIG. 9 is an enlarged detailed view taken from the boxed area 9 shown on FIG. 7;

FIG. 10 is a right-side view of the tabletop corner shown in FIG. 8;

FIG. 11 is a left-side view of the tabletop corner shown in FIG. 8;

FIG. 12 is a top view of the tabletop corner shown in FIG. 8; and,

FIG. 13 is a bottom view of the tabletop corner shown in FIG. 8.

The evenly dashed broken line illustrates environment that form no part of the claimed design. The dot-dash broken lines represent the boundaries of the claim and form no part thereof.

1 Claim, 13 Drawing Sheets
